UNITED STATES PATENT OFFICE.

THOMAS S. SMITH, OF ST. LOUIS, MISSOURI.

DESIGN FOR A DISINFECTANT-RECEPACLE.

SPECIFICATION forming part of Design No. 23,734, dated October 23, 1894.

Application filed September 4, 1894. Serial No. 522,136. Term of patent 7 years.

To all whom it may concern:

Be it known that I, THOMAS S. SMITH, of the city of St. Louis, State of Missouri, have invented a new and original Design for Disinfectant-Receptacles, of which the following is a full, clear, and exact description, reference being had to the accompanying drawing, forming a part hereof.

The drawing is a perspective view of a receptacle showing my design.

The leading feature of my design is a main vertical body, which is semi-circular in cross-section, from the lower end of which depends a smaller body which is also semi-circular in cross-section.

1 indicates the body of the receptacle which is semi-circular in cross-section and provided at its top and bottom and at different points in its length with ribs or beads 2. Extend-

ing vertically upward from the top of the body portion 1 is a projection 3. Depending from the central portion of the main body portion 1 is a smaller body 4 which is also semi-circular in cross-section and has formed therein the vertical rib or bead 5, and depending from this rib or bead is a projection 6. On the front side of the main body 1 is a shield-shaped figure 7.

What I claim is—

The design for a disinfectant receptacle, as herein shown and described.

In testimony whereof I affix my signature in presence of two witnesses.

THOMAS S. SMITH.

Witnesses:

E. E. LONGAN,
MAUD GRIFFIN.
